(57) **CLAIM**

I claim the ornamental design for a phone case, as shown and described.

DESCRIPTION

FIG. 1 is a perspective view of a phone case showing my new design;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depicting a hang strap, zipper, and zipper pull represent portions of the phone case that form no part of the claimed design. The broken lines shown on the central rear surface of the wallet portion of the phone case represent stitching that forms a part of the claimed design. The broken lines shown on the upper right corner of the phone case represent portions of the phone case that form no part of the claimed design.
